UNITED STATES PATENT OFFICE.

LOUIS J. HUGUES, OF TOPEKA, KANSAS.

STEERING-WHEEL LOCK.

Application filed January 29, 1923. Serial No. 615,655.

To all whom it may concern:

Be it known that I, LOUIS J. HUGUES, a citizen of the United States, residing at Topeka, in the county of Shawnee and 5 State of Kansas, have invented new and useful Improvements in Steering-Wheel Locks, of which the following is a specification.

This invention relates to a steering wheel 10 lock for motor vehicles, the general object of the invention being to provide combination means for retaining the locking bolt in locking position with means for changing the combinations whenever desired.

Another object of the invention is to so 15 arrange the parts that all the screws which fasten the different parts in position will be covered by locked parts when the device is in locking position.

This invention also consists in certain 20 other features of construction and in the combination and arrangement of the several parts, to be hereinafter fully described, illustrated in the accompanying drawings 25 and specifically pointed out in the appended claims.

In describing my invention in detail, reference will be had to the accompanying 30 drawings wherein like characters denote like or corresponding parts throughout the several views, and in which:—

Figure 1 is an elevation of a steering column of an automobile showing the invention in use.

Figure 2 is a plan view with the steering wheel removed.

Figure 3 is a longitudinal sectional view.

Figure 4 is a section on line 4—4 of Figure 3.

Figure 5 is a section on line 5—5 of Figure 3.

Figure 6 is a section on line 6—6 of Figure 3.

Figure 7 is a detail view.

In these views 1 indicates the steering shaft, 2 the wheel carried thereby, 3 the column and 3' the gear housing at the upper end of the column.

In carrying out my invention I place a 50 casing 4 on the housing 3', said casing being secured to a bushing 5 by a screw 6,

the said bushing 5 taking the place of the cover of the gear housing and being secured in position by the screws 6. This screw 6 is covered by the housing so that it is impossible to remove the screw with the housing in place. A locking bushing 7 is keyed to the shaft 1 by the key 8 and this bushing carries a keeper recess 9. This bushing is enclosed by the casing 4. The casing is provided with a tubular extension 10 which forms a bearing for a barrel 11. The end of the barrel covers the screw 6 so as to prevent removal of the screw as long as the barrel is in place and said barrel is 55 rotatably held on the extension by the screw 12 engaging an annular groove 13 in the extension. Both the barrel and extension are provided with window openings 14. A locking bolt 15 passes through the extension and through a bore 16 in the casing and said bolt is held against rotary movement by means of a screw 17 carried by the casing and which engages a slot 18 in the bolt. The inner end of the bolt is adapted 60 to engage the keeper recess 9 when forced inwardly by a cam part 19 in the barrel engaging the head 20 of the bolt. The head is provided with a recess 21 for receiving the cam part when the barrel is in a certain 65 position and the bolt is retracted by the spring 22 which is placed upon the head of the bolt and a ring 23 which is placed in the tubular extension. The combination rings 24 engage the bolt and each ring has 70 a key-way 25 therein and an annular groove 26 at one end which communicates with the key-way and the bolt is provided with a plurality of keys 27 which cooperate with the key-ways and grooves, it being understood 75 that when the keys are in engagement with the grooves the rings can be rotated on the bolt and that unless the key-ways are in alignment with each other the bolt cannot be moved. Each combination ring carries an engraved collar 27 which is adjustable to the ring by means of the screw 28 which engages a threaded hole 29 in the ring and a half bushing 30 which frictionally engages the collar when the screw is 80 tightened and thus firmly holds the collar to the ring. The screws can be reached by 85

a screw driver which will pass through a hole 31 in the head of the bolt. The characters on the engraved collar appear through the windows 14 and an indication 5 mark 32 is placed on one wall of the window of the extension for setting the rings. A pin 33 is placed in a hole 34 in the casing and the outer end of the pin engages an annular recess 35 in the barrel. The locking 10 bolt is provided with a recess 36 for receiving the inner end of the pin when the bolt is in retracted position which will permit the pin to come into register with a groove 37 in the end of the barrel so that 15 the barrel can be withdrawn, when the bolt is in retracted position, by removing the pin 12. When the bolt is in projected position the pin 33 will prevent removal of the barrel even though the pin 12 has been 20 removed.

From the above it will be seen that the bolt can be projected by rotating the barrel so as to cause its cam to leave the recess 21 in the head of the bolt and thus force the 25 bolt inwardly against the action of its spring 22. This will cause the inner end of the bolt to engage the recess 9 and thus lock the steering wheel against movement. Then by turning the combination rings the retraction 30 of the bolt will be prevented. These rings can be rotated when the bolt is in projected position as the keys of the bolts engage the annular grooves 26 in the rings. When it is desired to unlock the wheel the combination 35 rings are turned until the proper combination characters are in line with the mark 32 which will place the key-ways in alignment with each other and with the keys on the locking bolt. Then the barrel is turned 40 until the cam comes opposite the recess 21 in the head of the bolt and then the spring 22 will retract the bolt. To lock the wheel again it is simply necessary to turn the barrel to project the bolt and then return the 45 combination rings to lock the bolt in projected position. The barrel is provided with knurled rings 11' for facilitating its rotation. As before stated the fastening screws are all covered so that it is impossible to unlock the steering wheel by disassembling the 50 parts though the parts may be disassembled when the locking bolt is in retracted position.

It is thought from the foregoing description that the advantages and novel features of my invention will be readily apparent.

I desire it to be understood that I may make changes in the construction and in the combination and arrangement of the several 60 parts, provided that such changes fall within the scope of the appended claims.

What I claim is:—

1. A steering wheel lock comprising a housing, a tubular extension, a locking bolt 65 slidably mounted in the extension and part

of the housing, a keeper part connected with the steering wheel for receiving the end of the locking bolt, a spring for normally holding the locking bolt in retracted position, a barrel rotatably mounted on the extension 70 and having a part thereon for pushing the bolt inwardly against the action of the spring, said bolt having a recess for receiving said part when the bolt is retracted and combination means for holding the bolt in 75 projected position.

2. A steering wheel lock comprising a housing, a tubular extension, a locking bolt slidably mounted in the extension and part 80 of the housing, a keeper part connected with the steering wheel for receiving the end of the locking bolt, a spring for normally holding the locking bolt in retracted position, a barrel rotatably mounted on the extension and having a part thereon for pushing the 85 bolt inwardly against the action of the spring, said bolt having a recess for receiving said part when the bolt is retracted and combination means for holding the bolt in projected position, such means consisting of 90 rings placed on the bolt and having key-ways and annular grooves therein, keys on the bolt for engaging the key-ways and grooves and a collar having indicating characters thereon adjustably connected with 95 each ring.

3. A steering wheel lock comprising a casing adapted to be connected with a part of the steering mechanism of a motor vehicle, a tubular extension on said casing, a bolt 100 slidably mounted in the extension and casing, a keeper part for the bolt connected with the steering wheel, spring means for holding the bolt in retracted position, a barrel rotatably mounted on the extension, said 105 barrel and extension having window openings therein, a cam part on the barrel for engaging a part of the bolt for projecting the same, a recess in the bolt for receiving said cam, combination rings on the bolt having portions appearing through the window openings and means for locking the barrel to the extension when the bolt is in projected position.

4. A steering wheel lock comprising a 115 casing adapted to be connected with a part of the steering mechanism of a motor vehicle, a tubular extension on said casing, a bolt 120 slidably mounted in the extension and casing, a keeper part for the bolt connected with the steering wheel, spring means for holding the bolt in retracted position, a barrel rotatably mounted on the extension, said barrel and extension having window openings therein, a cam part on the barrel for engaging a part 125 of the bolt for projecting the same, a recess in the bolt for receiving said cam, combination rings on the bolt having portions appearing through the window openings, means for locking the barrel to the exten- 130

sion when the bolt is in projected position, such means consisting of a pin carried by the casing and having its outer end engaging the annular groove in the barrel and the 5 bolt having a recess therein to receive the inner end of the pin when the bolt is in retracted position so that the outer end of the

bolt will disengage the groove in the barrel and means for connecting the barrel to the extension for preventing the barrel leaving 10 the extension when the bolt is in retracted position.

In testimony whereof I affix my signature.
LOUIS J. HUGUES.
